Primary Examiner—A. Hugo Word*Assistant Examiner*—Celia A. Murphy*Attorney, Agent, or Firm*—Kurt R. Benson[57] **CLAIM**

The ornamental design for an infant's robe, as shown and described.

DESCRIPTION

FIG. 1 is a front elevational view of an infant's robe embodying my new design;

FIG. 2 is a rear elevational view thereof;

FIG. 3 is a top plan view thereof;

FIG. 4 is a bottom plan view thereof;

FIG. 5 is a right side elevational view thereof; and,

FIG. 6 is a left side elevational view thereof.

The broken lines shown throughout the views are understood to represent conventional stitching lines.

FIG. 1

FIG. 2

FIG. 3

FIG. 4

FIG. 5
